HOLDER FOR WORK ORDER PAPERS

Arthur E. Maybrun, Santa Rosa, Calif.

Application October 10, 1957, Serial No. 48,059

Term of patent 14 years

(Cl. D58—26)

Fig. 1 is an elevational view of the holder for work order papers showing my new design;

Fig. 2 is a top plan view thereof;

Fig. 3 is a bottom plan view thereof.

I claim:

The ornamental design for a holder for work order papers, as shown.
